ABSTRACT OF THE DISCLOSURE

A cartridge holder carton in the form of a sleeve with opposed narrow cartridge-receiving top and bottom walls each provided with holes in staggered relationship to the holes in the other wall, and connecting side walls. Each hole is surrounded by a lip which supports the cartridge and frictionally engages it in a push fit. In the case of flanged cartridges the holes are on the top and bottom walls so that the flange rests on top of the walls where it is accessible for gripping to remove the cartridge. In the case of rimless cartridges, the lip engages in the groove near the base of the cartridge and the side walls adjacent to the top and bottom walls have openings forming extensions of those on the top and bottom walls to facilitate removal of the cartridge.

This invention relates to cartridge packages.

Various devices have been developed for holding cartridges. Containers made of paperboard have been suggested with openings to receive the cartridges and hold them in spaced position. However, packages of this nature have usually suffered from one disadvantage or another or have been unduly complex. It is an aim of the present invention to provide a simple and convenient container which can be easily made from foldable sheet material and is handy in use.

According to the invention, a carton is provided made from a single sheet of foldable material, preferably paperboard. The carton has parallel side walls spaced apart substantially the width of a cartridge and intervened by narrow top and bottom walls. The top and bottom walls are provided with openings just large enough to receive cartridges, each opening being surrounded by a shoulder of the carton material which serves to engage the cartridge and hold it in place. The openings in the top wall are staggered in respect of the openings in the bottom walls so that the cartridges are interdigitated.

One form of carton is intended for cartridges having a rim and the openings are just large enough to take the cartridge in a push fit while the rim rests on the shoulders surrounding the opening. The cartridge can be removed by grasping the shoulder and pulling it out.

In another form of container for rimless cartridges the openings continue from the top and bottom ends down the sides for a distance to provide access to the side of the cartridge to facilitate removal. In this case the cartridge is retained by the shoulder surrounding the opening engaging in the annular groove in the cartridge.

The invention features a special blank for making the carton, the carton itself in the form of a special sleeve, a complete package including the carton and cartridges, and several of these packages in a common container.

The invention will be described in more detail by reference to the accompanying drawings which illustrate preferred embodiments, and in which:

FIGURE 1 is a perspective view of a cartridge package according to the invention;

2

FIGURE 2 is a vertical cross-section along the line 2—2 of FIGURE 1;

FIGURE 3 is an enlarged fragmentary cross-section along the line 3—3 of FIGURE 1 at the top of the package;

FIGURE 4 is an enlarged fragmentary cross-section partly in elevation along the line 4—4 of FIGURE 1 showing the way in which the cartridge nests in one of the openings and is engaged by the shoulder surrounding the opening;

FIGURE 5 is a view of the blank to make the carton for the type of cartridge package shown in FIGURE 1;

FIGURE 6 is a perspective view of another preferred form of cartridge package according to the invention;

FIGURE 7 is a vertical cross-section partly in elevation along the line 7—7 of FIGURE 6;

FIGURE 8 is a fragmentary cross-section partly in elevation showing the nesting of a rimless cartridge and the engagement of the shoulder surrounding the cartridge-receiving opening in the groove of the rimless cartridge; and

FIGURE 9 is a view of the blank to make the carton for the type of cartridge package shown in FIGURE 6.

Referring more particularly to FIGURES 1 to 5 of the drawings a package of flanged or rimmed cartridges F is shown. The carton for this preferred cartridge package is made of a single sheet of foldable sheet material, preferably paperboard, the blank being shown in FIGURE 5. The holder is in the form of a sleeve A having side walls 15 and 17 interconnected at top and bottom, by walls 19 and 21.

The sleeve is formed from a blank B, shown in FIGURE 5, by folding about the creases 19a, 19b, 21a, 21b, and overlapping the terminal flaps 31 and 33 so as to provide a side wall 17. The joint is preferably midway of the side wall 17 as shown, although it could be placed close to the end wall 21 in which case the overlapping extension of the wall 21 would be more in the nature of a flange on the end wall than a major part of the side wall. The top and bottom walls 19 and 21 are provided with spaced apart openings 23 and 25 respectively, preferably slightly less in diameter than the barrel of the cartridge, surrounded by supporting shoulders 23a and 25a.

The rim 16 of each cartridge F sits on the shoulder 23a or 25a as the case may be, as shown in the drawing, with the sides 18 of the cartridge frictionally gripped by the shoulders in a push fit.

The top openings 23 are staggered with respect to the bottom openings 25 so that cartridges F inserted in the openings 23 will be interdigitated with cartridges F1 inserted in the openings 25.

Another form of holder, as illustrated in FIGURES 6 to 9, is adapted for rimless cartridges R. Similar parts of this holder have been given reference numerals with the same digits and tens as those in FIGURES 1 to 5, but raised by one hundred.

The frangible sleeve is shown as A1, the blank as B1. A joint 131 is provided midway of the wall 117, but could be near the wall 121 as explained earlier in connection with FIGURE 5. The joint is made by providing the margin of one terminal flap 131 of the blank B1 with a strip 128 of adhesive resistant coating material, having spaced apart spots 130 without such coating, and providing the other terminal flap 133, spaced from its edge with a line of adhesive 132. When the adhesive 132 is activated and the strips 141, 143 juxtaposed, the strip 143 adheres to the spots 142 so as to provide an interrupted and disengageable connection between the terminal flaps. The margin of the flap 117a is provided with a pull tab 145. A crease is provided between the flap 117a proper and the tab 145 to facilitate bending the latter away from the wall

of the carton, so that the joint 131 can be broken and the package opened. The flap 117b is provided with a slot 147 adapted to receive the tab 145 so that the package can be reassembled after a cartridge is removed.

Spaced apart openings 123 and 125 extend across the top and bottom walls 119 and 121 respectively, each opening also extending partly down the sides 117. The reason for having the openings extend down the sides is for finger access to the annular groove 116 in the rimless cartridge R to pull it out of the holder. With the rimmed cartridge one can grasp the rim 16 resting on top of the shoulder 23a or 25a, but this is not so possible with the rimless type. With the rimless cartridge, the groove 116 around the rim is engaged by the shoulders 123a or 125a of the openings 123 and 125 which are of a diameter slightly less than the diameter of the cartridge body 119 requiring the cartridge to be forced into place against the resilience of the material causing the shoulder around the opening to snap into the groove, as shown in FIGURE 8. The openings 123 extend down the side 117 far enough to give ready access to the groove 124 in the cartridge for its ready removal but not far enough to destroy the natural spring of the sheet material in the side walls.

The material from which the blank is made is foldable sheet material. The preferred material is paperboard which has enough snap in it to give holding power to frictionally engage the cartridges. Prior to filling the cartridges, the assembled and glued sleeve A, A1, will be relatively stiff and will tend to retain its flat form with the sides of the sleeve juxtaposed and must be forced into opened-out position against the resistance of the board. Depending on the board used, creases 19a, 19b, 21a, 21b, 119a, 119b, 121a, 121b between the respective panels of the blank may give adequate bending properties, but with the preferred board of a comparatively stiff material it may be desirable to include skip cuts 47, or 147 along the ceases to render them suitably flexible.

Another aspect of the invention, not specifically shown in the drawings is the combination of a plurality of cartridge packages in a common container. Alternatively, the individual packages may be wrapped, for example, in paper a transparent plastic material.

In putting the package together the blank is made into a sleeve and the terminal ends glued together as described. The sleeve normally lies flat with the sides 15 and 17, or 115 and 117 as the case may be, juxtaposed and retained in this position by the stiffness of the board. To load the carton with the cartridges, the sleeve is squared up so that the top and bottom 19 and 21, or 119 and 121 as the case may be, perpendicular to the sides 17, 15 or 117, 115 and the cartridges plowed into the openings 23, 25 or 123, 125 either manually or by mechanical means. The package thus resulting can then be assembled with other packages into a box containing a number of packages as, for example, shown in FIGURE 9.

A main advantage of the construction shown is the simplicity of the package. There are no excess parts and the manufacture and setting up of the blank is simple.

Both the flanged cartridges and the rimless cartridges have characteristics permitting them to be accommodated by a package of the same general nature. Each type of cartridge has a base provided with an annular shoulder facing the tip of the cartridge adjoining an annular body area of lesser diameter. In the case of the flanged cartridge, the annular shoulder is the under or forward side of the flange and the adjoining annular body area is the immediate area of the cylindrical body. In the case of the rimless cartridge, the annular shoulder is the forwardly facing part of the groove in the cartridge and the annular body area of lesser diameter is the bottom of the groove. The openings for the flanged cartridges extend right across the cartridge-receiving walls, whereas the openings for the rimless cartridges are spaced from the one edge of the cartridge-receiving walls and at the other side extend from the cartridge-receiving walls a short distance down the adjacent side walls.

We claim:

1. A package for cartridges of a type having a base provided with an annular shoulder facing the tip of the cartridge adjoining an annular body area of lesser diameter, comprising, a sleeve of pliable sheet material having a pair of opposed elongated rectangular cartridge-receiving walls of substantially the width of the cartridge body and provided with a plurality of spaced apart cartridge-receiving openings each surrounded by a lip, the openings being of a size for the lip to bear against a cartridge shoulder with the margin of the lip frictionally gripping the annular body area of lesser diameter, and parallel walls slightly longer than the cartridge extending between and connecting the cartridge-receiving wall, the openings in one cartridge-receiving wall being staggered with respect to the openings in the other, cartridges in said package each having a body extending through an opening in the sleeve with said cartridge shoulder carried by the lip and said annular body area of lesser diameter frictionally gripped by the margin of the lip to resist removal.
2. A package of cartridges, as defined in claim 1, which is a package of flanged cartridges and the openings terminate at the sides of the cartridge-receiving walls.
3. A cartridge package, as defined in claim 1, which is a package of rimless cartridges each having a groove near the base providing the shoulder and adjacent annular body area, a parallel wall adjacent each cartridge-receiving wall being provided with openings each forming an extension of an opening in the cartridge-receiving wall to provide access to a cartridge from the side.
4. A carton for cartridges of the type having a base provided with an annular shoulder facing the tip of the cartridge adjoining an annular body area of lesser diameter, comprising a sleeve of pliable sheet material made up of a pair of opposed elongated rectangular cartridge-receiving walls of substantially the width of the cartridge body and provided with a plurality of spaced-apart cartridge-receiving openings each providing a surrounding lip to engage a cartridge, the openings being of a size to receive a cartridge resting on the lip with the edge of the lip frictionally gripping said adjoining annular part of the cartridge, and parallel walls slightly longer than a cartridge extending between and connecting the cartridge-receiving walls, the openings in one cartridge-receiving wall being staggered with respect to the openings in the other.
5. A carton, as defined in claim 4, adapted for flanged cartridges in which the openings terminate at the sides of the cartridge-receiving walls.
6. A carton, as defined in claim 5, which is for rimless cartridges each having a groove near the base providing the shoulder and adjacent annular body area, a parallel wall adjacent each cartridge-receiving wall being provided with openings each forming an extension of an opening in the cartridge-receiving wall to provide access to the cartridge from the side.
7. A blank of foldable sheet material for forming a carton for cartridges of a type having a base provided with an annular shoulder facing the tip of the cartridge adjoining an annular body area of lesser diameter, said blank being cut and creased to provide the parts of the carton and including a pair of spaced-apart narrow parallel panels of substantially the width of the cartridge body each provided with spaced-apart openings staggered with the openings in the other panel and adapted to form cartridge-receiving walls, between said narrow panels an elongated panel of substantially the length of a cartridge, and at the opposite sides of the narrow panels from the elongated panel terminal panels adapted to be connected together to form a second elongated wall to complete the carton, the cartridge-receiving openings being surrounded by a lip each being adapted to receive a cartridge with the lip bearing against the cartridge shoulder and the edges of the lip gripping the annular adjoining area.
8. A blank, as defined in claim 7, in which the open-

ings are entirely on the cartridge-receiving walls so that they are adapted to receive flanged cartridges.

9. A blank, as defined in claim 8, in which said elongated panel and a narrow panel are provided with openings forming continuations of openings in the narrow panels whereby the resulting carton is adapted to contain rimless cartridges.

10. A package, as defined in claim 3, in which one parallel wall is formed by overlapping inner and outer flaps extending from the respective cartridge-receiving walls and releasably secured together adhesively, said outer flap being provided at its terminal edge with a tab and the inner flap being provided spaced from its terminal edge with a slot adapted to receive said tab.

11. A carton, as defined in claim 6, in which one parallel wall is formed by overlapping inner and outer flaps extending from the respective cartridge-receiving walls and releasably secured together adhesively, said

outer flap being provided at its terminal edge with a tab and the inner flap being provided spaced from its terminal edge with a slot adapted to receive said tab.

12. A blank, as claimed in claim 9, in which said terminal panels are adapted to be overlapped and temporarily connected together adhesively, one of said terminal panels being provided at its terminal edge with a tab and the other of said terminal panels spaced from its terminal edge with a slot adapted to receive said tab.
